UNITED STATES PATENT OFFICE.

OTIS H. STARNER, OF CARLISLE, PENNSYLVANIA.

CORRECTIVE SHOE AND ARCH SUPPORT THEREFOR.

Application filed January 28, 1926. Serial No. 84,265.

This invention relates to a corrective shoe and to a metatarsal arch support to be used in such a shoe, and it has for one of its objects to provide a shoe having built into it a novel arch-supporting member which will support both the transverse metatarsal arch and the longitudinal arch of the foot, and also to provide a novel filler or supporting member which may be readily built into the shoe and which is so constructed that its proper position in the shoe is determined by its relation to the in-seam-receiving lip of the insole.

The features wherein the invention resides will be more fully hereinafter set forth and the novel features thereof will be pointed out in the claims.

In the drawings, wherein I have illustrated an embodiment of my invention, Fig. 1 is a side view, partly broken out, of a shoe having my improvements embodied therein;

Fig. 2 is a bottom plan view of a shoe embodying my invention and having a portion of the outsole broken out to illustrate the manner in which the proper position of the arch-supporting member is determined;

Fig. 3 is a top plan view of the supporting member;

Fig. 4 is a section on the line 4—4, Fig. 3; Fig. 5 is a section on the line 5—5, Fig. 3; Fig. 6 is a section on the line 6—6, Fig. 3; Fig. 7 is a section on the line 7—7, Fig. 3.

In the drawings 1 indicates a shoe having the usual outsole 2 and insole 3. Situated between the insole 2 and outsole 3 is a filler member 4 embodying my invention. Said member is preferably made of rubber so that it will be somewhat resilient and it has the special shape shown.

The outer edge 5 of said member is convexly curved from the front 6 to the rear edge 7. The inner edge is convexly curved, as shown at 8, from the point 6 to an intermediate point 9 and is concavely curved from the point 9 to the rear edge 7, as shown at 10. At the front of the filler, the two convexly curved edges 5 and 8 meet in a point 6, while at the rear end, the sides 5 and 10 are separated somewhat from each other, thus forming the straight rear edge 7. This provides a member which is widest at the central portion and which tapers to a point at the front, while the rear end 11 forms a sort of shank portion. The under face 12 of the supporting member or filler 4, or that side which rests on the outsole 2, is

made flat. The upper face, which rests against the insole, is rounded so that the member 4 is thickest at the center. The central portion of said member, indicated at 14 in Fig. 3, has a flat upper face and from the peripheral edge of this flat portion 14 the upper face curves toward the edges, as shown at 15. This rounded or curved upper portion 15 of the filler member is such that on the convex edges 5 and 8, the top and bottom faces meet in a relatively sharp edge, while at the concavely curved edge 10 the filler member has an appreciable thickness, as shown best in Figs. 4 and 7.

In making a welt shoe having the improved arch-supporting member therein said shoe will be lasted in the usual way and the welt 20 will then be sewed to the in-seam-receiving rib 21 by the in-seam stitches 22, all as usual in welted operations. Before the outsole 2 is applied the arch-supporting member 4 is placed in position as shown in Fig. 2 with the concave edge 10 of appreciable thickness resting against the inside of the in-seam-receiving rib 21. The arch-supporting member 4 is placed so that the point 9 comes just back of the ball of the foot and with the shank portion 11 extending up the shank of the foot.

The arch-supporting member is so designed that the curved edge 10 will fit the curve of the in-seam-receiving rib at the shank and when it is placed as shown in Fig. 2 with the edge 10 resting against the inner face of the in-seam-receiving rib said support will be properly positioned to give the desired support not only to the metatarsal arch but also to the longitudinal arch of the foot.

The in-seam-receiving rib thus operates as a guide for correctly positioning the arch-supporting member and the edge 10 constitutes a positioning edge, thus facilitating the correct positioning of said member in the manufacture of the shoe.

Since the in-seam-receiving rib 20 is approximately parallel to the edge of the outsole the concave edge 10 of the arch-supporting member 4 will lie substantially parallel to the edge of the sole.

In the manufacture of shoes embodying this invention I propose to use lasts 18 which are made with a slight hollow at the point where the support 4 is to be placed, as shown at 19 in Fig. 1. The advantage of this is that in the making of the shoe, the

outer sole will be laid flat, while the inner sole will be raised at the point where it passes over the metatarsal arch support and will thus be given the proper contour to give the desired support to the metatarsal arch.

I claim:

1. A welt shoe having an insole provided with an in-seam-receiving rib, an outsole and an arch-supporting member of resilient material situated between the insole and outsole, the outer edge of said member having a convex curvature from the front to the rear and the inner edge being convexly curved from the front to a point intermediate the front and rear and concavely curved from the latter point to the rear, the concavely curved edge resting against and being positioned by the in-seam-receiving rib at the shank of the shoe, said member having a flat under face resting on the outsole and being thickest at its central portion.
2. A welt shoe having an insole provided with an in-seam-receiving rim, an outsole and an arch-supporting member of resilient material situated between the insole and outsole, the outer edge of said member having a convex curvature from the front to the rear and the inner edge being convexly curved from the front to a point intermediate the front and rear and concavely curved from the latter point to the rear, the concavely curved edge resting against and being positioned by the in-seam-receiving rib at the shank of the shoe, said member having a flat under face resting on the outsole and the central portion of the upper

face also being flat, the marginal portions of said upper face tapering toward the under face and meeting said under face at the convexly curved edges but being separated from said under face at the concavely curved positioning edge, whereby the latter has an appreciable thickness.

3. An arch-supporting member for a shoe, said member being made of resilient material and being longer than it is wide and having a square rear end and a pointed forward end, the outer edge of said member being convexly curved from the square rear edge to the pointed front end and the inner or opposite side presenting a convex curve extending from the pointed end to a mid position and a concave curve extending from said mid position to the square rear end, said member having a flat under face and the central portion of the upper face which is opposite the junction of the convex and concave curves being flat, said upper face curving toward the under face at the marginal portions and meeting the under face along the convex edges, the concavely curved portion of the edge being of appreciable thickness and constituting a positioning edge which is adapted to rest against the insole-receiving rib of the shoe at the shank portion thereof thereby to position the member in the shoe with the forward pointed end thereof located in position to support the transverse arch of the foot.

In testimony whereof, I have signed my name to this specification.

OTIS H. STARNER

outer sole will be laid flat, while the inner sole will be raised at the point where it passes over the metatarsal arch support and will thus be given the proper contour to give the desired support to the metatarsal arch.

I claim:

1. A welt shoe having an insole provided with an in-seam-receiving rib, an outsole and an arch-supporting member of resilient material situated between the insole and outsole, the outer edge of said member having a convex curvature from the front to the rear and the inner edge being convexly curved from the front to a point intermediate the front and rear and concavely curved from the latter point to the rear, the concavely curved edge resting against and being positioned by the in-seam-receiving rib at the shank of the shoe, said member having a flat under face resting on the outsole and being thickest at its central portion.

2. A welt shoe having an insole provided with an in-seam-receiving rim, an outsole and an arch-supporting member of resilient material situated between the insole and outsole, the outer edge of said member having a convex curvature from the front to the rear and the inner edge being convexly curved from the front to a point intermediate the front and rear and concavely curved from the latter point to the rear, the concavely curved edge resting against and being positioned by the in-seam-receiving rib at the shank of the shoe, said member having a flat under face resting on the outsole and the central portion of the upper

face also being flat, the marginal portions of said upper face tapering toward the under face and meeting said under face at the convexly curved edges but being separated from said under face at the concavely curved positioning edge, whereby the latter has an appreciable thickness.

3. An arch-supporting member for a shoe, said member being made of resilient material and being longer than it is wide and having a square rear end and a pointed forward end, the outer edge of said member being convexly curved from the square rear edge to the pointed front end and the inner or opposite side presenting a convex curve extending from the pointed end to a mid position and a concave curve extending from said mid position to the square rear end, said member having a flat under face and the central portion of the upper face which is opposite the junction of the convex and concave curves being flat, said upper face curving toward the under face at the marginal portions and meeting the under face along the convex edges, the concavely curved portion of the edge being of appreciable thickness and constituting a positioning edge which is adapted to rest against the in-seam-receiving rib of the shoe at the shank portion thereof thereby to position the member in the shoe with the forward pointed end thereof located in position to support the transverse arch of the foot.

In testimony whereof, I have signed my name to this specification.
